UNITED STATES PATENT OFFICE.

HARRY ROBERT NORTHOVER, OF WINNIPEG, MANITOBA, CANADA.

GAS-LEVER-OPERATING MECHANISM FOR USE IN CONNECTION WITH CERTAIN TYPES OF MACHINE-GUNS.

1,207,612.

Specification of Letters Patent.

Patented Dec. 5, 1916.

Application filed November 23, 1915. Serial No. 63,105.

To all whom it may concern:

Be it known that I, HARRY ROBERT NORTHOVER, subject of the King of Great Britain, residing at 217 Graham avenue, Winnipeg, Manitoba, in the Dominion of Canada, gunsmith, have invented certain new and useful Gas-Lever-Operating Mechanism for Use in Connection with Certain Types of Machine-Guns, of which the following is

10 a specification.

In gas-operated machine or automatic guns of the "Colt" type, the automatic working of the gun is effected by the pressure of the powder gases in the barrel acting, through 15 a piston contained in a barrel-vent, upon a "gas-lever" which is fulcrumed to the body of the gun, below the front part of the barrel, so as to be capable of swinging in a vertical plane thereunder, and is mechanically 20 connected with the breech mechanism. This gas-lever, has, however, to be actuated by hand for performing any operations incidental to the working of the gun beyond those effected by the action of the powder 25 gases during the actual firing. For instance, the lever has to be manually operated for transferring the first cartridge from a new feed-belt into the feed-block; also for re-loading after a stoppage; also for ejecting 30 any live cartridge that may remain in the barrel after the removal of the belt or after a misfire; also for ejecting jammed cartridge cases. The manual actuation of the 35 gas-lever is thus frequently necessary when the gun is in action, and it follows from the fact that the lever is located at the front or muzzle end of the barrel that, if the gun is being fired over the parapet of a trench or from behind other cover, either one of the 40 gun-crew must dangerously expose himself, or firing must be delayed by withdrawing the gun from position, every time the gas-lever requires to be worked by hand.

The present invention consists in an attachment or mechanism which can be readily applied to existing "Colt" or like automatic guns, and which provides for the manual operation of the gas-lever from the rear or breech end of the gun, thus obviating unnecessary exposure of any member of the gun-crew or any disturbance of the aim of the gun when the said lever has to be actuated by hand. The attachment also enables the gas-lever to be easily and rapidly manipulated in trenches or other confined po-

sitions. The said attachment or mechanism comprises a system of gearing which is mounted preferably on the left-hand side of the front part of the body of the gun, and is connected with the gas-lever and an operating cable which is extended from the gearing, through suitable guides, to the breech end of the said gun, where it is furnished with a hand-loop or the like whereby a pull may be conveniently imparted to the cable 60 for working the gear whenever it is required to operate the gas-lever independently of the gas-pressure system. This lever-operating gear is constructed so that no part of the same moves when the gas-lever is actuated 65 automatically.

Figure 1 of the accompanying drawing represents a general view of a "Colt" automatic gun fitted with a gas-lever operating attachment constructed in accordance with 75 one form of my invention. Fig. 2 is an elevation, on an enlarged scale, of the forward part of the body of the gun and the mechanism which is mounted thereon; the said mechanism being shown, partly in section 80 and partly in elevation, with its elements in the positions they assume normally and also when the gas-lever is working automatically, i. e., independently of the hand-operating mechanism. Fig. 3 is a detail view, showing 85 the connection between the gas-lever of the gun and the levering arm or cam of the hand-operating mechanism. Fig. 4 is a plan of Fig. 2. Fig. 5 is an end view of the same, and Fig. 6 is a sectional view of a part of 90 the mechanism taken upon the dotted line x, Fig. 2.

The same letters of reference indicate corresponding parts in the several figures of the drawing.

In these figures, a is the body of a "Colt" gun, on which the demountable barrel b is secured by the barrel-brackets b¹, b², and c is the gas-lever which is fulcrumed to the said body and is actuated (when the gun is working automatically) from a gas-piston contained in a gas-cylinder in the base of the barrel bracket b¹; the said lever being connected with the breech mechanism of the gun in the usual way.

The principal parts of the mechanism for operating the gas-lever by hand in accordance with the present invention is located, in the arrangement shown in the drawing, on the left-hand side of the body a; imme-

diately behind the gas-lever and it comprises a driving pinion *d* which is connected with an operating cable *e*, and a toothed sector *f* that meshes with the said pinion and carries 5 a rigid cam-arm or extension *g* adapted to connect with and act upon the said gas-lever. The driving pinion is mounted on the inner side of, and is rigidly connected to, a pulley or grooved disk *d*¹ which has 10 its bearing on a stud *d*² attached to the side of the gun-body, while its grooved periphery contains the forward end of the operating cable *e*; this extremity of the said cable being suitably fixed to the pulley so that when the 15 cable is drawn rearwardly, the said pulley and the driving pinion are turned through a corresponding arc of movement, while the toothed sector *f* is mounted on another stud *f*¹ on the body and its forward extension or 20 cam-arm *g* is arranged to bear upon the upper side of a rollered stud *h* which projects laterally from the forward end of the gas-lever. This arrangement admits of the 25 gas-lever swinging independently of the quadrant arm when the gun is working automatically, but when the cable is pulled for setting the gear in motion by hand, the gear compels the said cam-arm to make a downward and rearward angular movement in a 30 vertical plane, and to transmit a corresponding movement to the gas-lever which, in turn, operates the breech mechanism, while when the rearward pull on the cable is relieved, the gas-lever and the parts of the 35 gear are restored to their normal positions by the action of the gas-lever return springs that are embodied in the ordinary mechanism of the gun.

The cam-arm *g* may be provided with a 40 spring catch *i* or the like, which normally engages with a notch *i*¹ in the gun-body and prevents movement or displacement of any part of the operating gear when the gas-lever is being operated automatically while 45 the pulley and driving pinion may be inclosed within or protected by a case or cover *j* having two gaps or openings *j*¹, *j*², in its periphery; one for the operating cable to pass through and the other for the sector 50 member to work within. Or instead of the spring catch being carried on the arm, a similar device may be mounted on the body of the gun in such a position that on the cam-arm *g* being lifted into its normal or 55 out-of-action position by the spring-return motion of the gas-lever, the said cam arm is engaged by the catch and held stationary until the mechanism is again normally operated. The cable *e* works within a tubular 60 guide or sheath *e*¹ that is attached to the side of the gun-body either by clips *e*² as shown in the drawing, or by any other convenient means, while the rearward end of the same is attached to a leather hand-loop 65 *e*³ or the like to enable a member of the gun

crew to readily draw the said cable rearwardly from the breech end of the gun whenever it is required to actuate the gas-lever manually.

In the form of the invention shown in the drawings, the fulcrum studs of the gear elements *d* and *f* are constructed so that they can be attached or applied to existing guns by screws or the like, and the cover or casing of the gear is adapted to be similarly attached, but if desired, the whole of the parts may be constructed as a self contained unit in which the fulcrum studs and the cover are mounted on, or made as an integral part of a suitable base or attachment-plate. Further, instead of providing for the actuation of the driving pinion by a cable, any other mechanical means operable from the rear or breech end of the gun may be adopted for this purpose. The cable arrangement illustrated has, however, the advantage that it affords an effective and simple means for working an attachment suitable for application to existing guns.

Having described my invention, what I claim and desire to secure by Letters Patent is:—

1. A mechanism for manually operating the gas-lever of "Colt" type automatic guns, comprising a movable member mounted on the gun to engage with the gas-lever to actuate the same, and a manually operated means connected to said member for actuating the same from the rear end of the gun.

2. A mechanism for manually operating the gas-lever of automatic guns, comprising a movable member mounted on the gun to engage with the gas-lever to actuate the same, and a manually operated means connected to said member for actuating the same from the rear end of the gun, said member being arranged to remain stationary during the automatic operations of said gas-lever.

3. A mechanism for manually operating the gas-lever of automatic guns, comprising an arm pivotally mounted on the gun to engage with the gas-lever to actuate the same, a gearing operably connected with said arm for actuating the same, and a manually actuated member situated at the rear end of the gun and having an operative connection with said gearing, said arm being arranged to normally lie out of the path of movement of the gas-lever whereby said arm remains stationary during the automatic operations of said gas-lever.

4. A mechanism for manually operating the gas-lever of automatic guns, comprising an arm pivotally mounted adjacent the muzzle end of the gun and adapted to engage with said gas-lever when actuated, a toothed sector provided on one end of said arm, a pinion mounted on said gun to mesh with said sector, and manually actuated means for actuating said pinion and extending to

the breech end of the gun whereby said arm is actuated.

5. A mechanism for manually operating the gas-lever of automatic guns, comprising an arm pivotally mounted on the gun adjacent its muzzle end and adapted to engage with said gas-lever when actuated, a toothed sector provided on one end of said arm, a pinion mounted on said gun to mesh with 10 said sector, a grooved pulley associated with said pinion, an operating cable having one end secured to the pulley and adapted to pass over the groove therein, and guide means extending to the breech end of the 15 gun and through which said cable extends.
6. A mechanism for manually operating the gas-lever for "Colt" type automatic guns, comprising an arm pivotally mounted on the gun to engage with the gas-lever 20 to actuate the same, a gearing mounted on
- the gun and connected with said arm for actuating the same, a manually operated member situated at the rear end of the gun and having an operable connection with said gearing, said arm being actuated to 25 normally lie out of the path of movement of the gas-lever, and a spring detent carried by said arm and adapted to engage with the body of the gun for retaining the arm in its normal position and stationary 30 during the automatic operations of said gas-lever.

In testimony whereof I have hereunto set my hand in presence of two subscribing witnesses:

HARRY ROBERT NORTHOVER.
